UNITED STATES PATENT OFFICE.

PAUL W. BOSSART, OF MARIETTA, PENNSYLVANIA.

TELEPHONE CABINET AND SUPPORT.

SPECIFICATION forming part of Letters Patent No. 622,412, dated April 4, 1899.

Application filed February 11, 1898. Serial No. 669,914. (No model.)

To all whom it may concern:

Be it known that I, PAUL W. BOSSART, a citizen of the United States, residing at Marietta, in the county of Lancaster and State of Pennsylvania, have invented certain new and useful Improvements in Telephone Cabinets and Supports; and I do hereby declare the following to be a full, clear, and exact description of the invention, such as will enable others skilled in the art to which it appertains to make and use the same.

The chief objects of this invention are to provide for the convenient removal of the working machinery from an inclosing case and to adapt the transmitter-support to be turned and adjusted so that the mouthpiece may be presented wherever needed.

To this end the said invention consists in the combination of a removable part of a telephone-case with the operative mechanism attached thereto and with the body of the said case, also in the combination of a transmitter with its support, which is adapted to be adjusted and turned into any desired position and which may be attached to the said telephone-case, also in the construction and combination of divers details hereinafter more particularly set forth and claimed.

In the accompanying drawings, Figure 1 represents a perspective view of a telephone case or cabinet and attached parts embodying my invention, the front having been removed. Fig. 2 represents a similar view, the operative mechanism having been removed. Fig. 3 represents a detail view of the operative mechanism and the removable part of the case to which it is attached, the same being shown in front elevation on a larger scale. Figs. 4, 5, 6, and 7 represent detail views, in plan and front elevation, of certain electric connections, also enlarged. Fig. 8 represents a detail view of the adjusting devices for the transmitter.

A designates the body of the telephone case or cabinet, having its back extended upward to form a raised wall A'. A fixed horizontal partition A² divides the interior thereof into an upper compartment A³ and a lower compartment A⁴. The top of compartment A³ is formed by a horizontal shelf A⁵. On the inner face of one side wall of said upper compartment is a horizontal bead a. The parti-

tion A² is provided near its other end with a similar bead a', extending from front to rear. A strip of wood B, provided with contact plates or clips B' at intervals on its front face, is attached by screws b³ to the under side of partition or upper shelf A² at the front of the latter, these screws entering slots b⁴ in strip B, which allow endwise motion of the said strip. Each of these contact-plates has a threaded stud b, (which may be a filistered-head machine-screw,) projecting from its front, also binding-screws b' for wires b², leading to the necessary electrical connections. 65

A removable frame or slide C rests at one end on the bead a. It consists of a horizontal part and a vertical part C', the latter forming the other side wall of compartment A³ and resting on the partition A² just outside 70 of the bead a', which prevents it from being moved inward too far. This removable angular slide or frame thus constitutes an easily-detachable part of the case. It is provided on the exterior of its vertical wall C' with the 75 usual gravity-hook D, supporting the receiver E, and also with the bell F, the alarm mechanism G being attached to the inner side of the said vertical wall. To the under side of the horizontal upper part of the said removable 80 frame or slide I secure a magneto-machine H. In the lower compartment A⁴ is the battery I. The horizontal upper part of said removable slide or frame is provided with contact plates or clips C², having hooks c' formed on them, 85 which are respectively arranged and adapted to catch on the studs b of contact-plates B' when the said slide or frame is moved a little to the left from the position shown in Fig. 5 into the position shown in Fig. 6. Each of these plates C² is provided with a binding screw or post c² for the attachment of a wire J, leading to the magneto-machine, bells, and gravity-hook aforesaid. 90

The wires b² of plates B' are connected in 95 any suitable manner by the necessary conductors to the line, the battery, the transmitter, and the receiver, so that when the removable slide or frame C is in its place and the contact-plates B' and C² are engaged, as aforesaid, the working mechanism attached to the said removable frame will be in proper electrical connection with the battery transmitter and receiver, these last three elements or de-

5 vices being attached to the main body A of the case or cabinet. To provide for conveniently and detachably securing the said removable slide or frame to the body of the case without using additional devices, I slightly screw out the studs or screws b, permitting the engagement of the hooks c' therewith, as described, and afterward tighten these screws again, so as to bind the plates B' and C² securely together. Thus the said plates, with their hooks and screws, become fastening-clips for the removable part of the case and its attachments.

10 The induction-coil case K of the transmitter is attached to the raised rear wall A' of the case and provided with a lug K', to which the bent arm L of the transmitter M is pivoted on a bolt or pintle O, allowing to the said arm a rotary movement through a half-circle.

15 20 The boss L' of the arm is recessed at l to contain a semicircular spring or its equivalent N, one end of which is attached to the lug K' of the coil-case, the other end being attached to the said arm within the said boss in such manner that it will operate to hold the said arm upward. While the arm is in place, the lug K closes the outer side of the recess l and protects the said spring. The bolt O is provided with a nut O' and passes through 25 a brake-disk P on the opposite side of the said boss. By the said nut the said bolt is made to draw this disk against the said boss to a greater or less degree, whereby the augmented friction may be used to compensate for any 30 35 weakening of the said spring incident to continued strain and wear. The transmitter M, attached to the outer end of this arm, has thus a partial vertical adjustment, and the curved neck R, supporting the trumpet-mouthpiece S, has a horizontal adjustment, as shown in dotted lines, Figs. 1 and 2. By the above construction of the supporting parts the transmitter may be raised and lowered and the mouthpiece turned horizontally, so that the 40 45 telephone may be placed in the corner of a room or in any other place which might otherwise be impracticable or inconvenient, for the mouthpiece may be easily turned out of such corner or place to reach the mouth of the user.

50 55 These improvements are of course applicable to any kind of transmitter whether used with the case or cabinet or not; but there is an obvious advantage in utilizing the case as a support for the transmitter in the ordinary way.

I do not claim any novelty in the battery, the magneto-machine, the ringing mechanism, or the receiver. Any ordinary forms of devices for effecting the same general results 60 may be substituted.

The removability of a part of the case or cabinet and the operating mechanism attached thereto greatly facilitates inspection and repair and allows any part which may be 65 out of order to be taken from the dark corner where the telephone is most likely to be found into brighter light for such purposes.

Moreover, the removable part of the instrument may be exchanged at once for another in good working order, so that the interruption of transmission is reduced to the least possible time. 70

These improvements will save considerable expense and trouble to the installing company and annoyance to all concerned. 75

The braking-disk hereinbefore described is preferably of brass and should have some resiliency to insure proper mechanical and electrical contact.

Having thus fully described my invention, 80 what I claim as new, and desire to secure by Letters Patent, is—

1. In combination with the body of a telephone-case, a removable slide or sliding frame forming part of the said case and consisting 85 of a horizontal part and a vertical part or wall, the operative mechanism being attached to the said removable part so that it may be removed therewith substantially as set forth.

2. In combination with the body of a telephone-case having a series of contact-plates, a removable slide, forming part of said case provided with a corresponding series of such plates adapted to be in contact with the former series, operative mechanism attached to 95 the said removable part and conductors making circuit through the said mechanism and said plates substantially as set forth.

3. In combination with the body of a telephone-case and a part removable therefrom 100 and carrying the operative mechanism, interlocking plates attached to said part and said body and means for completing an electric circuit through the said plates, the latter serving to hold the said parts of the case together as well as to close the circuit. 105

4. In combination with the body of a telephone-case provided with fixed plates, having studs formed on them, which are adapted to screw in and out, a removable slide, forming part of the side wall of the said case having the operative mechanism attached thereto and also provided with hooks that catch over the said studs, the parts of the case being fastened together detachably by tightening 110 said screws or studs on the said hooks, and these interlocking parts also serving to close the electric circuit substantially as set forth. 115

5. A telephone case or cabinet having a removable part or section adapted to slide in and out of the said case and forming when in position a part of the side wall of the latter to which the magneto-machine and alarm mechanism are attached, the said removable 125 part and body being also provided with jointly-operating circuit-closing devices that serve in addition as clips to hold the said parts of the case together substantially as set forth.

6. In combination with a telephone-transmitter and its supporting-arm, a pivotal joint for horizontal motion, whereby the neck of the transmitter-mouthpiece is connected 130

to said arm, a pivotal joint for vertical motion, whereby the said arm is attached to a fixed support, and a spring acting on the said arm to raise the same substantially as set forth.

5 7. In combination with a device adapted to be attached to a support and having a forward-extending part K', a transmitter-supporting arm having on one side of the boss L' at its inner end a recess which is closed when in use by the said part K', a pivot-bolt O which passes through the said boss and said part K', allowing vertical motion of the said arm, a spring N, coiled in the said recess, attached 10 to the said part and the said arm, and acting to raise the latter, a friction-disk P drawn by the said bolt against the said arm and a trans-

mitter carried by the said arm substantially as set forth.

8. A transmitter-supporting arm having its 20 inner end recessed at one side and normally closed by a part of a fixed device to which it is attached, in combination with a spring contained within the said recess and operating to lift the said arm, a transmitter-mouthpiece and a pivotal joint connecting said mouthpiece to said arm and allowing horizontal motion substantially as set forth.

In testimony whereof I affix my signature in presence of two witnesses.

PAUL W. BOSSART.
